UNITED STATES PATENT OFFICE.

JOHN G. WILLET, OF BUFFALO, NEW YORK.

CARBURETING APPARATUS.

1,333,050.

Specification of Letters Patent.

Patented Mar. 9, 1920.

Application filed January 24, 1917. Serial No. 144,267.

To all whom it may concern:

Be it known that I, JOHN G. WILLET, a citizen of the United States, residing at Buffalo, in the county of Erie and State of New York, have invented new and useful Improvements in Carbureting Apparatus, of which the following is a specification.

This invention relates to a carbureting apparatus designed for use in connection with internal combustion engines, but more particularly for use in connection with the motors of automobiles. It is especially desirable for the heavier liquid fuels, such as kerosene, but is not limited to that use.

In engines of this type, the pressure in the working ends or compression chambers of the cylinders varies with the load, being greater as the load increases and less as it diminishes.

The object of my invention is the provision of a reliable carbureting apparatus which utilizes this variable air pressure to automatically govern the quality or richness of the explosive mixture, in order to adapt it to the varying engine loads and thus obtain practically perfect combustion and prevent waste of fuel.

In the accompanying drawings: Figure 1 is a diagrammatic view of the apparatus with the engine shown in top plan and the carbureter and other parts in elevation. Fig. 2 is an enlarged vertical section of the carbureter. Fig. 3 is a horizontal section on line 3—3, Fig. 2. Fig. 4 is a vertical longitudinal section of the pressure regulator. Fig. 5 is a transverse section thereof on line 5—5, Fig. 4.

Similar characters of reference indicate corresponding parts throughout the several views.

The carbureter shown by way of example in the drawings, is provided with two float chambers 1 and 2, the former for gasoline used principally in starting and the latter for kerosene or other low grade fuel, used at other times.

3 indicates the main chamber of the carbureter provided with the usual air inlet or intake 4 and with the mixing or Venturi tube 5. Arranged in the bottom of the chamber 3 is a sump or fuel well 6 to which leads a supply passage 7 having branches 8 and 9 connected with the float chambers 1 and 2, respectively. The customary controlling valve 10 is arranged at the junction of these passages for delivering either gaso-

lene or kerosene to the well or shutting the same off from both chambers.

Projecting centrally from the well 6 is a fuel nozzle 11 which is connected with the upper end of an upright fuel passage 12 supplied from the well by the passage 7. Within this nozzle is an ordinary needle valve 13 having a screw threaded stem 14 or other suitable means for adjusting it.

15 indicates an air or atomizing nozzle surrounding the fuel nozzle 11 and secured in the bottom of the well 6. These nozzles are separated by an intervening space or passage 16 to which air under pressure is supplied for the purpose of drawing the kerosene or other fuel through the nozzle 11 and spraying or atomizing it. This is accomplished, preferably by the following mechanism:

17 indicates an internal combustion engine of the four-cycle type and 18 an air pump of any ordinary construction which is suitably driven from the crank shaft of the engine. This pump may be of the piston or plunger type and delivers the compressed air into a suitable air chamber or reservoir 19. The discharge pipe 20 of this chamber leads to a valve chamber 21 formed in a suitable casing 22 and having a discharge passage 23 which is connected with the atomizer passage 16 by a pipe or conduit 24 and a passage 25. This valve chamber is provided at its discharge end with a seat 26 to which is applied a regulating valve 27, the stem of which passes through a cap or head 28 in which it is guided. A spring 29 surrounding this stem between the valve and the cap 28 tends to close the valve. The latter is opened to a greater or less extent by a piston 30 reciprocating in a pressure cylinder 31 formed in the lower portion of the casing 22. The stem 32 of this piston is connected by a yoke 33 with the stem of the valve 27, so that the latter is moved in unison with the piston. 34 indicates a spring interposed between the piston and the head or plug 35 which closes the front end of said cylinder. This spring resists the forward movement of the piston. The pressure cylinder 31 is connected with the working ends of the compression chamber of the engine cylinder 17 by suitable conduits, so that the pressure in said chamber acts upon the piston 30 which thereby responds to the varying load of the engine and in turn opens the regulating valve correspondingly, thus regulating the

force of the blast through the atomizing nozzle 15 and the amount of fuel delivered by the atomizer. In the construction shown in the drawings, a four-cylinder engine is 5 shown and each cylinder is provided in its top with the usual valved priming cup 36. The pipes leading from these cups into the cylinder are provided with lateral connections 37 containing suitable check valves 38, 10 and from these valves extend air pipes or manifolds 39 which in turn are connected with the pressure cylinder 31 by pipes 40 and 41.

Located in the mixture outlet 42 of the carbureter is the customary throttle valve 43. With this valve is preferably combined an auxiliary fuel supply passage 44 connected by a pipe 45 with the gasoline float chamber 1. This passage 44 forms an idler jet which 20 is practically inactive in the normal open position of the throttle valve when the engine is running on kerosene or other low grade fuel. When, however, the throttle is nearly closed, as shown in Fig. 2, the increased air 25 velocity draws a sufficient quantity of fuel through said passage to prevent stalling of the engine which is liable to occur when the kerosene supply is throttled comparatively low.

30 As shown in Fig. 4, the pressure cylinder 31 is provided at its rear end with an exhaust passage 46 having a suitable regulating valve 47.

In the use of the apparatus, the proper fuel 35 level is maintained in the well 6 in the customary manner. Upon starting the engine, the air pump 18 supplies compressed air to the atomizer of the carbureter, drawing the fuel from the nozzle 11 and producing the explosive gas, as hereinbefore described. As 40 the pressure cylinder 31 of the regulator 22 is connected with the working ends of the engine cylinders 17, the piston in said pressure cylinder is advanced more or less against the resistance of the springs 29 and 34, opening 45 the regulating valve 27 accordingly and delivering a more or less powerful air blast through the nozzle 15, with the result that a correspondingly lean or rich explosive mixture is produced. As the pressure in the 50 working ends of the cylinders varies with the engine load, the fuel supply to the carbureter is thus automatically regulated or governed by it, the mixture being richest and most powerful, for example, in starting an automobile equipped with this apparatus or in climbing a hill, and becoming leaner as the car gathers speed or runs at medium or high speed upon a level road. As the air blast 55 delivered by the atomizing nozzle grows stronger under increased loads, it has sufficient power to thoroughly break up the increased fuel charges, thereby producing a practically perfect mixture and complete combustion under all conditions, avoiding

waste of fuel and effecting a corresponding economy in the consumption of gas. This results not only in an important saving, but enables the car to be promptly started, because the engine at that time is under heavy 70 load and automatically produces the necessary rich and powerful gas mixture for that purpose.

The resistance of the springs 29, 34 is properly regulated to obtain these results, 75 the plugs 28 and 35 having screw threaded connection with the casing 22 for this purpose, or being made adjustable by other suitable means.

In coasting or running down hill, the load 80 is nearly removed from the engine and the air pressure is comparatively low. Very little fuel is therefore drawn through the nozzle and no waste occurs, as in ordinary carbureters which draw an excessive quantity 85 under the same conditions, not only wasting it but also producing a disagreeable noise in the muffler.

Owing to this automatic governing of the atomizer by the engine load, the needle 90 valve 13 when once adjusted, ordinarily requires no further regulation.

Although the several cylinders of the engine successively deliver compressed air to the controlling piston 30 of the pressure regulating valve 27, the pressure upon the piston is practically continuous.

It will be observed that the air pressure delivered to the atomizer is drawn from a source other than the engine cylinders, with 100 the result that the air is comparatively clean and not liable to clog the passages of the carbureter or the conduit between the source of pressure and the carbureter.

The carbureter and other parts of the apparatus may be modified within the scope 105 of the appended claims, and I do not therefore wish to be limited to the particular construction herein shown and described.

I claim as my invention:

1. In a carbureting apparatus, the combination of an internal combustion engine, a carbureter having a fuel atomizer, a source of air pressure, a conduit connecting said atomizer with said pressure-source, a 115 regulating valve in said conduit, and actuating means for said valve governed by the varying pressure in the working ends of the engine-cylinders.

2. In a carbureting apparatus, the combination of an internal combustion engine, a carbureter having a fuel atomizer, a source of air pressure, a conduit connecting said atomizer with said pressure-source, a regulating valve in said conduit, a pressure cylinder connected with the working ends of the engine cylinders, and a piston in said pressure cylinder responsive to the varying pressure in the engine-cylinders and controlling said regulating valve.

3. In a carbureting apparatus, the combination of an internal combustion engine, a carbureter having a fuel atomizer, a source of air pressure, a conduit connecting said atomizer with said pressure-source, a regulating valve in said conduit, opening means for said valve controlled by the varying pressure in the working ends of the engine cylinders, and a spring tending to close 10 said valve.
4. In a carbureting apparatus, the combination of an internal combustion engine, a carbureter having a fuel atomizer, a source of air pressure, a regulator comprising a casing 15 containing a valve chamber and a pressure cylinder, said valve chamber being connected with said pressure source and having an outlet connected with said atomizer, a valve in said valve chamber controlling the passage of air to said atomizer, a piston in said pressure cylinder, a yoke operatively 20 connecting said valve and piston, a spring tending to close said valve, and a conduit connecting said pressure cylinder with the working ends of the engine cylinders.
5. In a carbureting apparatus, the combination of an internal combustion engine, a carbureter having a fuel atomizer, a source 25
- of air pressure, a regulator comprising a casing containing a valve chamber and a pressure cylinder, said valve chamber being 30 connected with said pressure source and having an outlet connected with said atomizer, a valve in said valve chamber controlling the passage of air to said atomizer, a piston in said pressure cylinder, a yoke operatively 35 connecting said valve and piston, a spring tending to close said valve, and a conduit connecting said pressure cylinder with the working ends of the engine cylinders.
6. In a carbureting apparatus, the combination with an internal combustion engine, of a carbureter comprising a chamber having a fuel atomizer, a throttle-valve and an auxiliary fuel passage controlled by said valve, separate float chambers for supply- 40 ing different grades of fuel to the atomizer, a source of pressure, a conduit connecting said atomizer with said pressure source, regulating means in said conduit governed by the varying load of said engine, and a conduit connecting said auxiliary fuel passage with one of said float-chambers. 45

JOHN G. WILLET.
